United States Patent Office.

GEORGE R. MENEELY, OF WEST TROY, NEW YORK.

Letters Patent No. 80,422, dated July 28, 1868.

IMPROVEMENT IN ATTACHING BELLS TO THEIR YOKES.

The Schedule referred to in these Letters Patent and making part of the same.

TO ALL WHOM IT MAY CONCERN:

Be it known that I, GEORGE R. MENEELY, of West Troy, in the county of Albany, and State of New York, have invented a new and useful Improvement in Bell-Yokes, of which the following is a full and exact description, reference being had to the accompanying drawing, in which—

Figure 1 is a sectional elevation, and

Figure 2 a perspective view of a part of a bell hung in a yoke, which embodies the distinguishing feature of my invention, and

Figures 3, 4, and 5 are perspective views of parts thereof, like parts being marked by the same letters in the various figures.

This invention relates to that class of bell-yokes in which the bell and its clapper are secured to a cap-plate, which turns with the bell whenever the bell is loosened, and turned in the yoke to make the clapper strike in a new place on the bell, and consists in securing the centre-bolt, which holds the clapper, to the said movable cap-plate, by means of devices substantially such as hereinafter described, so that whenever the bell and cap-plate shall be loosened, turned, and refastened in the yoke, to present a different part of the circumference of the bell to the blows of the clapper, the centre-bolt, which holds the clapper, can then be readily released from the cap-plate, turned into the position where the clapper will swing in or nearly in the same plane as the bell swings in ringing, and there re-secured to the cap-plate so effectually that the clapper will not get out of its proper position.

In the aforesaid drawing, A is a bell, cast with a round tapering shank, B, at its top, which fits in a corresponding aperture in a yoke, C.

The bell is secured in the yoke to a cap-plate, D, partly by a screw-bolt, E, which supports a clapper, F, and extends up through a central opening in the cap-plate and bell-shank, and partly by auxiliary screw-bolts, G, figs. 2, 4, 5, which fit in recesses H, cast in the shank of the bell, and extend up through separate holes in the cap-plate, said bolts being provided with nuts, I J, which screw down upon the cap-plate directly or indirectly. The central hole through the cap-plate and top of the bell is large enough to allow the bolt E, which holds the clapper, to be turned around therein, and the tightening of the nut or nuts I is not always or generally sufficient to keep the bolt E from getting turned, so as to let the clapper swing out of its proper position within the bell.

To keep the clapper in its proper position in all cases, whatever part of the circumference of the bell may be set opposite to the clapper, the bolt E, fig. 3, which holds the clapper, is so squared, or shaped and fitted with a corresponding washer, K, that the bolt and washer must turn together if at all, and the washer K is formed with teeth or indentations along its periphery, and is thereby firmly held by a clutch, L, and set-screw, M, attached to the cap-plate D, which supports the bell in the yoke.

To make the clapper strike on a new place in the circumference of the bell, first unscrew the nuts I J, of the central and lateral bolts, so that the bell drops a little in the yoke, and then grasp the bell at its rim, and turn it in the yoke to any desired position. The bolts and cap-plate will of course turn with the bell. Next, screw down the nuts of the lateral bolts G, and loosen the clutch L from the washer K of the centre-bolt E, and turn back the clapper F, with the centre-bolt and its washer, so that the clapper will swing in the same or nearly the same plane as the bell swings in ringing, and finally screw down the nut or nuts on the centre-bolt, and reset the clutch L upon the washer K, and the bell will be again in ringing order.

In carrying out my invention I construct the adjustable clutch L M, or its equivalent, and attach it to the cap-plate D in any suitable form and manner. For instance, instead of having the clutch-piece L slide radially between dove-tail lugs N, the clutch-piece may be pivoted to the cap-plate, and turned in and out on its pivot-centre, and held in the teeth or indentations of the washer K by a set-screw or a clamp-screw; and, as an equivalent for the adjustable clutch L M, I sometimes leave out the part L, cast the nut-lug O, fig. 1, on the cap-plate, nearer to the washer K, and have a pointed end on the screw M enter into the teeth or indentations of the washer. In fig. 1, P is a check-nut on the screw M.

By securing the centre-bolt to the cap-plate in various positions, by means of a toothed or indented washer attached to the centre-bolt, in combination with an adjustable clutch or its equivalent attached to the cap-plate, as hereinbefore described, I avoid the awkwardness and inconvenience heretofore experienced of having a fixed arm or key attached to and extended from the centre-bolt outward over the bolts and nuts on the cap-plate to the body of the yoke, to keep the clapper in its proper position within the bell.

What I claim as my invention, and desire to secure by Letters Patent, is—

Securing the centre-bolt, which holds the clapper, to the cap-plate, which turns with the bell and supports it in various positions in the yoke by means of a toothed or indented washer attached to the centre-bolt, in combination with an adjustable clutch attached to the cap-plate, substantially as herein set forth.

In testimony whereof, I hereunto set my hand, this 7th day of April, 1868.

GEO. R. MENEELY.
